CLAIM

The ornamental design for a game controller, as shown and described.

DESCRIPTION

FIG. 1 is a front, right side, top perspective view of the game controller embodying my new design;
FIG. 2 is a rear, right side, top perspective view thereof;
FIG. 3 is a front elevation view thereof;
FIG. 4 is a rear elevation view thereof;
FIG. 5 is an enlarged left side elevation view thereof;
FIG. 6 is an enlarged right side elevation view thereof;
FIG. 7 is a top plan view thereof;
FIG. 8 is a bottom plan view thereof;
FIG. 9 is a perspective thereof, showing the article in use; and,
FIG. 10 is another perspective thereof, showing the article in use.

The broken lines shown in the figures depict portions of the game controller that form no part of the claimed design.
